UNITED STATES PATENT OFFICE

JULIUS E. STOLL, OF MILWAUKEE, WISCONSIN, ASSIGNOR TO PABST CORPORATION, OF MILWAUKEE, WISCONSIN, A CORPORATION OF WISCONSIN

LABELING MECHANISM

Application filed January 12, 1931. Serial No. 508,073.

The invention relates to label affixing apparatus.

The object of the invention is to provide a simple and effective apparatus for affixing 5 labels to packages or containers that are mounted on an intermittently moving conveyor or carrier. More particularly the invention provides a labeling apparatus including a paste applying arm and a label applying 10 arm so associated that the apparatus may be used as an attachment for packaging machines.

The invention further consists in the several 15 features hereinafter set forth and more particularly defined by claims at the conclusion hereof.

In the drawings, Fig. 1 is a plan view of the apparatus embodying the invention, parts being broken away;

20 Fig. 2 is an end elevation view of the apparatus, parts being broken away;

Fig. 3 is a detail sectional view taken on the broken line 3—3 of Fig. 2;

25 Fig. 4 is a detail side elevation view as viewed in the direction of line 4—4 of Fig. 2;

Fig. 5 is a detail side elevation view as viewed in the direction of line 5—5 of Fig. 2;

30 Fig. 6 is a detail sectional view taken on the line 6—6 of Fig. 3.

Referring to Figs. 1 and 3, the numeral 8 designates an intermittently movable conveyor or carrier here shown as a rotary table mounted to revolve on a standard 9 and having a Geneva stop wheel 10 associated therewith which is engaged by the pin 11 on a crank arm 12 of a vertically disposed suitably journalled rotatable shaft 13 which carries a gear 14 meshing with a gear 15 on a drive shaft 16 adapted to be driven by any suitable source of power. As shown in Fig. 1, the table 8 has a series of cavities 17 formed therein adapted to carry the package to be labeled past the labeling apparatus embodying the 45 invention.

Referring to Fig. 2, the numeral 18 designates a paste arm carrying standard and 50 19, a label arm carrying standard and each of these arms are slidably and rotatably mounted in the framework 20 of the labeling attach-

ment and adapted to swing and move vertically relative to the table 8.

The standard 18 carries an arm 21 provided with a head 22 in which paste receiving pins 23 are loosely mounted and adapted to be moved into cooperative engagement with a paste feeding wheel or drum 24 mounted on a shaft 25 and adapted to dip into a supply trough 26 containing the adhesive.

The shaft 25 has a sprocket mounted thereon over which a chain 27 runs, said chain also running over another sprocket 28 mounted on a shaft 29 carrying a bevel gear 30 meshing with a bevel gear 31 on a shaft 32 which is suitably journalled in the casing 33 and carries a bevel gear 34 meshing with a bevel gear 35 on the main drive shaft 16.

The standard 19 carries an arm 36 provided with a suction finger or head 37 adapted to be moved into cooperative relation with a stack 70 of labels and the article upon which the label is to be affixed.

The standard 19 has a gear 38 suitably slidably keyed thereto and meshing with a smaller gear 38' similarly keyed to the standard 18 so that when one of said standards is turned, the other will be also through a different arc of movement. For turning these standards in proper timed relation with the other parts of the mechanism, the standard 19 has a crank arm 39 secured to the lower end thereof and having an articulated joint connection through the horizontally disposed pin 40, block 41 pivoted thereon to a link 42 vertically pivoted by pins 43 to the block, said link at its other end having a similar connection through vertically disposed pins 44, block 45 to a pin 46 on the free end of a lever 47 pivotally mounted at 48 on the casing 33. This lever carries a roller 49 held in engagement with an operating cam 50 by a spring 51, said cam being mounted on a shaft 52 carrying a worm wheel meshing with a worm 54 on the shaft 31. The oscillation of the lever 47 by the cam 50 acts through the linkage above described to oscillate the standard 19 which through the gears 38 and 38' oscillates the standard 18 which moves through a wider arc of travel than the standard 18, it being noted that because of 100

the articulated connections of the link 42, the standards may also be moved vertically at the same time.

For moving the standard 19 vertically, it will be noted from Fig. 3 that said standard has a collar 55 mounted thereon, carrying a pivot bolt 56 that is connected with a lever 57 pivotally mounted at 58 on the casing 33 and carrying a roller 59 held in engagement with a cam 60 on the shaft 52 by a suitable spring 61.

Referring to Fig. 4, the standard 18 is moved vertically through the lever 62 pivoted at 63 to the casing 33 and carrying a pivot bolt 64 mounted on a collar 65 on said standard, said lever carrying a roller 66 held in engagement with a cam 67 on the shaft 52 by a spring 68.

The levers 57 and 62 are also adapted to be adjustably limited in their downward movement by adjustable stop bolts 69 and 70 respectively.

The labels are carried in a stack 71, open at one side, and the top of this stack has one or more projecting ledges 72 of usual construction to resist the free movement of the topmost label but permit it to be released by the proper agency. The labels are fed upwardly by a plunger 73 whose stem or rod 74 is slidably mounted in a frame member 75 and at its lower end said rod carries an arm 76 connected by a tension spring 77 with a bracket 78 fixed to the member 75 so that whenever permitted to do so, the plunger under the action of the spring 77 will act to feed the labels upwardly. Control of this feeding action is effected by a clamping means engageable with and releasable from the rod 74 and under the control of the lever 57. As shown in Figs. 2 and 5 the rod 74 is mounted between a fixed block 79 secured to the member 75 and a movable block 80 which are normally held in clamping engagement with the rod 74 by tension springs 81 connected to opposite sides of said blocks. The movable block 80 is secured to a shaft 82 suitably journaled in bearings 83 on the member 75 and carrying a crank arm 84 having a pin and slot connection 85 with a link 86 connected to the lever 47. Thus during a certain portion of the cycle of movement of the lever 47 the block 80 will be moved out of engagement with the rod 74 and thus permit the plunger 73 to exert a feeding action on the labels.

For removing the labels from the stack one at a time, the head 37 is connected to a pipe terminal 87 having a nipple 88 connected by flexible tubing or piping 89 to a suitable vacuum valve 90 having a nipple 91 for connection by suitable piping with a suitable vacuum pump not shown. As the construction of the vacuum valve forms no part of the present invention, it will suffice to mention that the movable element of said

valve has an operating arm 92 associated therewith and controlled by a cam 93 mounted on the shaft 52 and against which said arm is held by a spring 94. The terminal 87 also has a nipple 95 connected by flexible piping 95 to a suitable valve 96 which controls the supply of compressed air introduced from any suitable source of supply by a pipe not shown, connected to a nipple 97 leading into the valve casing, the valve being normally closed and having a projecting stem 98 disposed in the path of a finger 99 on a collar 100 carried by the standard 19.

With the above construction during the time the table is moving between its indexing positions the cam 50 acts on the lever 47 and thence through the link 42 and standard 18, gears 38 and 38' to swing the standards 18 and 19 and their arms 21 and 36 from the full line positions shown in Fig. 1 to the dotted line positions there shown while said arms 21 and 36 are in an elevated position and then the cams 60 and 67 allow the arms to descend thereby bringing the pins 23 into contact with adhesive on the roll 24 over which said pins may swing as they move into and out of contact therewith and at the same time bringing the head 37 over the top of the stack of labels in the stack 71. The suction valve 90 is then opened by the cam 93 and with the table 8 at rest the cams 60 and 67 raise the standards 18 and 19 and said standards are then swung under the action of the cam 50, inwardly over the table as shown in full lines in Fig. 1 and then the arms 21 and 36 are lowered to a depositing position with reference to the article to be labeled, then presented in cavities 17 beneath said arms. As the arm 21 lowers, the pins 23 contact with the article and deposit two spots of adhesive or paste thereon and as the arm 36 lowers, the head 37 brings the label over these spots of glue, previously deposited on another article, and the suction is released and as the standard 18 completes its downward stroke the stop 99 strikes the valve stem 98 and opens the compressed air valve and compressed air then flows into the head 37 and blows on the label or applies a blast of air thereto with sufficient force to press the label on the adhesive coated portion of the article to establish an attached relation therewith. Thereafter the arms 18 and 19 are again moved to elevated position and the cycle of operations is repeated.

I desire it to be understood that this invention is not to be limited to any particular form or arrangement of parts except as such limitations are included in the claims.

What I claim as my invention is:

1. In a label applying mechanism, the combination with an intermittently moving conveyor for the articles to be labeled, of an adhesive applying arm, a label carrying arm, means for swinging said arms to a position to

respectively receive adhesive and a label and to position to deposit adhesive and said label, means for also separately raising and lowering said arms, said label carrying arm having a head provided with a connection with a source of suction and with a connection with a source of compressed air, and means for separately controlling said sources of connection.

2. In a label applying mechanism, the combination with an intermittently moving carrier for the articles to be labeled, a pair of standards mounted adjacent said table for swinging and vertical movement relative thereto, an adhesive applying arm carried by one of said standards, a source of adhesive supply, a label applying arm carried by the other of said standards, a holder for labels, means for simultaneously turning said standards to bring said adhesive applying arm into an operative position with said source of adhesive and to bring said label applying arm over said holder and for moving said standards to bring said arms into depositing positions over the table with reference to the articles to be labeled thereon; means for raising and lowering said arms from and to the positions above mentioned, and means associated with the label applying arm for assisting in carrying and depositing the label.

3. In a label applying mechanism, the combination with an intermittently movable carrier for the articles to be labeled, of a pair of standards mounted adjacent said table for swinging and vertical movement relative thereto, an adhesive applying arm carried by one of said standards, a source of adhesive supply, a label applying arm carried by the other of said standards, a holder for labels, means for simultaneously turning said standards to bring said arms into position to respectively receive adhesive and a label and for turning said standards to bring said arms into depositing positions over the table with reference to the articles to be labeled thereon, means for raising and lowering said arm from and to the positions above mentioned, said label carrying arm having a head provided with a connection with a source of suction and with a connection with a source of compressed air, valves for controlling said sources of connection, and means on the standard of said label applying arm for operating the said valve to control the supply of compressed air to said head.

4. In a label applying mechanism, the combination with an intermittently movable carrier for the articles to be labeled, of a pair of standards mounted adjacent said table for swinging and vertical movement relative thereto, an adhesive applying arm carried by one of said standards, a source of adhesive supply, a label applying arm carried by the other of said standards, a holder for labels, a gearing connection between said standards

for simultaneously turning one from the other, means for turning one of said standards and thus turning both of said standards into and out of receiving and applying positions, and means for raising and lowering said standards while in said positions.

5. In a label applying mechanism, the combination with an intermittently movable carrier for the articles to be labeled, of a pair of standards mounted adjacent said table for swinging and vertical movement relative thereto, an adhesive applying arm carried by one of said standards, a source of adhesive supply including a drum, means for rotating said drum, said arm provided with pins engageable with said drum and adapted to transfer spots of adhesive therefrom to the article to be labeled, a label applying arm carried by the other of said standards, a holder for labels, means for simultaneously turning said standards to bring said pins into operative position with said drum and to bring said label applying arm over said holder and for moving said arms into depositing positions with reference to the articles to be labeled on said table, means for raising and lowering said arms from and to the positions above mentioned, and means associated with the label applying arm for assisting in carrying and depositing the label.

In testimony whereof, I affix my signature.
JULIUS E. STOLL.
